UNITED STATES PATENT OFFICE.

CHARLES J. HODGE, OF HOUGHTON, MICHIGAN.

DESIGN FOR A FRAME FOR SUPPORTING ORE OR MINERAL WASHING JIG-SCREENS.

SPECIFICATION forming part of Design No. 29,931, dated January 3, 1899.

Application filed December 12, 1898. Serial No. 699,071. Term of patent 7 years.

To all whom it may concern:

Be it known that I, CHARLES J. HODGE, a citizen of the United States, residing at Houghton, in the county of Houghton and State of Michigan, have invented and produced a certain new and original Design or Useful Shape for a Frame for Supporting Ore or Mineral Washing Jig-Screens, of which the following, in connection with the accompanying drawings, is a full, clear, and exact specification.

In the said drawings, Figure 1 is a plan view of a frame of the character described embodying my design. Fig. 2 is a transverse sectional view thereof, taken on the line 2 2, Fig. 1; and Fig. 3 is a side elevation, partly in longitudinal section, on the line 3 3, Fig. 1.

The leading features of my design consist of the screen-supporting frame, having the marginal frame A and the comparatively thin intermerged cross-bars B C, arranged at an angle to each other and being very thin as compared with their depth and also as compared with the thickness of the frame A.

The frame A is rectangular and oblong, and it is provided throughout at short intervals with sockets a, formed in its upper side, and throughout the distance between the points where the sockets a are formed and between such points and the points where the cross-bars B C adjoin the frame A it is curved or beveled downwardly on its inner side, as

shown at a', leaving around each socket a rounded boss a''.

The bars B extend transversely of the frame A and directly across from side to side, while the bars C extend longitudinally thereof, but each is as long only as the distance between two of the bars B, and they break joint with one another.

The frame A and the cross-bars B C are coterminus in depth, as shown in Figs. 2 and 3, so that their upper and lower surfaces will be flush or lie in the same planes, respectively, and the cross-bars B C besides being narrow as compared with the width of the frame A and as compared with their depth are tapered from bottom to top, and their top edges are rounded, as clearly shown in Figs. 2 and 3. At one end and at an intermediate point between the sides is formed a perforated boss D, which is located at one of the junctures of the bars B C.

Having thus described my invention, what I claim as new therein, and desire to secure by Letters Patent, is—

The design for a frame for supporting ore or mineral washing jig-screens substantially as herein shown and described.

CHAS. J. HODGE.
